R. B. BENJAMIN.
SHOW CASE LIGHTING DEVICE.
APPLICATION FILED NOV. 15, 1915.

1,266,908.

Patented May 21, 1918.

UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SHOW-CASE-LIGHTING DEVICE.

1,266,908.

Specification of Letters Patent.

Patented May 21, 1918.

Application filed November 15, 1915. Serial No. 61,646.

To all whom it may concern:

Be it known that I, REUBEN B. BENJAMIN, a citizen of the United States, residing at Chicago, in the county of Cook and State 5 of Illinois, have invented new and useful Improvements in Show-Case-Lighting Devices, of which the following is a full, clear, concise, and exact description, reference being had to the accompanying drawing, forming a part of this specification.

My invention relates to show case lighting devices.

One of the objects of my invention is to provide an improved device of this character which is made in sections and which can be quickly attached and detached to make a fixture of any length desired.

In the drawings, in which I have shown one embodiment of my invention—

20 Figure 1 is a section through a show case showing my improved lighting device located therein;

Fig. 2 is a section on the line 2—2 of Fig. 1;

25 Fig. 3 is a section on the line 3—3 of Fig. 2;

Fig. 4 is a section on the line 4—4 of Fig. 3;

30 Fig. 5 is a section on the line 5—5 of Fig. 2;

Fig. 6 is a section on the line 6—6 of Fig. 2;

Fig. 7 is a section on the line 7—7 of Fig. 1; and

35 Fig. 8 is a section on the line 8—8 of Fig. 1.

Referring now to the drawings in detail, the device as shown comprises a plurality of similar sections 10 electrically and mechanically connected together end to end and located in any suitable position within the show case. Each section 10 comprises a trough 11 within which the lamps are located, reflector members 12 located within 40 the trough 11, two receptacles 13 one at each end of the trough 11, electrical connections 14 for supplying current to the receptacles 13, two lamp sockets 15 one supported by and engaging each of the receptacles 13, and tubular lamps 16 and 17 lying in the trough 11 and inserted in the sockets 15.

The trough 11 comprises an elongated channel member 18 bent inwardly at 19 (Fig. 4) to hold the reflector members 12 in 45 position, and heads or caps 20 at the ends

of the channel members 18 to which the receptacles 13 are secured. These caps are secured to the channel members 18 in any suitable manner as by rivets 21. For holding the electrical connections 14 in their proper 60 position a channel member 22 is provided which channel member is held in position by means of the reflector members 12. A clip 23 is provided for supporting the bulb of the tubular lamp in the casing, which bulb 65 extends more than one half the length of the channel. This clip may be secured to the channel member 22 by means of an eyelet 24.

The receptacle 13 comprises an insulating base 25 secured to the cap 20 by means of 70 eyelets 26, spring contacts 27 for engagement with corresponding contacts on the lamp socket 15, said contacts being located in recesses 28 in the insulating base, terminal plates 29 to which the electrical connections 14 are soldered, screws 30 for electrically and mechanically connecting the plates 29 with the binding plates 31, and binding screws 32 for engagement with the leading-in wires. Only one of the insulating bases 25 80 of the entire fixture is provided with the binding screws 32. In the other bases the binding plates 31 serve as part of the mechanical and electrical connections between the sections 10 and for this purpose connecting and conducting screws 33 are provided (Fig. 6) having a threaded end 33^a and a reduced shank portion 33^b which is provided so that it will not be necessary to thread the screw through the plate 31 through which 90 it is first inserted for its entire length before it can engage the second plate 31.

The base 25 is provided with suitable channels 34 for the leading-in wires 35 and is suitably recessed at 36 to accommodate the 95 connections 14. The connections 14 comprise a pair of insulating conductors 37 the ends of which are secured to the plates 29 in any suitable manner as by soldering at 38.

The lamp socket 15 comprises an insulating base 39, shell and center contacts 40 and 41 supported by the base 39, eyelets 42 for securing the shell contact in place, contact blades 43 for engagement with the spring contacts 27 of the receptacle, and screws 44 100 for connecting the shell and center contacts with the contact blades 43. The spring contacts 27 and associated parts are so constructed that they will receive the contact blades of the cap of a separable attachment 110

plug if desired. The fixture may be secured in the corner of a show case 45 by means of suitable clips 46. It will be seen that by the use of these sections 10, a lighting device of any desired length may be built up and that these sections may be very easily mechanically and electrically connected by simply inserting the screws 33, two for each section after which the sockets 15 may be slipped in

10 place in the receptacles 13.

The connections 14 are made permanently at the factory before shipping and the receptacles 13 are also permanently secured to the caps 20. When the fixture is completely set up and connected the circuit is from one of the leading in wires 35 to the binding plate 31 through the screw 30 to the plate 29, through one of the conductors 37 to the corresponding plate 29 at the other end of the channel, through the corresponding screw 30, binding plate 31, screw 33 to the binding plate carried by the base 25 of the adjacent channel and so on throughout the succeeding sections. The lamps are connected in multiple between the conductors 37 from one of the plates 29 through the spring contact 27 engaging the plate 29, through the contact blade 43, screw 44, center contact 41, lamp circuit, shell contact 40, screw 44, contact blade 43, spring contact 27 to the other plate 29 and the other conductor 37. The spring contact plates 27 are so located with respect to the trough 11 that the lamp with its socket 15 may be swung outwardly from the trough 11 when it is desired to remove the lamp and insert another.

Having thus described my invention what I claim as new and desire to secure by Letters Patent is:—

40 1. In a device of the class described a channel member, means for supporting an electric lamp within said channel, said means including an insulating base adjacent one end of said channel, a second channel member, means for supporting an electric lamp therein, said means including an insulating base adjacent one end of said channel, and common means for mechanically connecting said channels together end to end forming a unitary structure and for electrically connecting the circuits of said lamps, said common means including a member extending through both said bases.

55 2. In a device of the class described a channel member, an insulating base supported therein, a binding plate supported by said base, a conductor plate also supported by said base, a conductor electrically connected to said conductor plate, a connecting member electrically and mechanically connecting said plates, and a contact member clamped between said base and conductor plate.

60 3. In a device of the class described two channel members placed together end to end, two insulating bases one in each channel

member, two conductors one for each channel, two conductor plates one for each conductor supported by said bases, respectively, two other plates one supported by each base, a connecting member electrically and mechanically connecting said last two plates, and two connecting members one for each base for electrically and mechanically connecting the plates supported by each base.

4. In a device of the character described, 75 two channel reflector members arranged end to end, four insulating bases, one at each end of each member, conducting means carried by each member extending between the insulating bases, and a member of conducting material extending through two adjacent bases, one in each member, for connecting said members together and electrically connecting said conducting means.

5. In a device of the character described, 80 two channel reflector members arranged end to end, four insulating bases, one at each end of each member, four conducting plates, one carried by each base, conducting means carried by each member electrically connecting the conducting plates, and a member of conducting material mechanically and electrically connecting two adjacent plates, one in each member.

6. In a device of the character described, 85 two channel reflector members arranged end to end, four insulating bases, one at each end of each member, four conducting plates, one carried by each base, conducting means carried by each member electrically connecting the conducting plates, and a member of conducting material extending through two adjacent bases, one in each member, mechanically and electrically connecting two of said plates, one in each member.

7. In a device of the class described, two sheet metal channel members arranged end to end, four insulating bases, one secured at each end of each member, four lamp sockets, one detachably secured to each base, conducting means electrically connecting the sockets of each channel member, and means for mechanically connecting together two adjacent bases, one in each channel, to form a unitary structure.

8. In a device of the class described, two sheet metal channel members arranged end to end, four insulating bases, one secured at each end of each member, four lamp sockets, one detachably secured to each base, conducting means electrically connecting the sockets of each channel member, and common means for mechanically connecting together two adjacent bases, one in each channel, to form a unitary structure, and for electrically connecting two of said sockets, one in each channel.

9. In a device of the character described, a channel reflector member arranged end to end, two insulating bases, one adjacent each

- end of said channel, two lamp receptacles, one supported by each base, each receptacle comprising center and side contacts for the lamp, and two conductors extending along 5 said channel member for electrically connecting the contacts of one receptacle with the contacts of the other, each lamp receptacle having a quickly detachable connection with its base.
10. 10. In a device of the character described, a channel reflector member, two insulating bases, one adjacent each end of said channel, two lamp receptacles, one supported by each base, each receptacle comprising center 15 and side contacts for the lamp, two conductors extending along said channel member for electrically connecting the contacts of one receptacle with the contacts of the other, a second channel member, two insulating bases, one adjacent each end of 20 said second channel member, two lamp receptacles, one supported by each base, each receptacle comprising center and side contacts for engaging the lamp, two conductors extending along said channel member for electrically connecting the contacts of one 25 receptacle with the contacts of the other, and common means for mechanically connecting said channel members together end to end to form a unitary structure and for electrically connecting the conductors of one channel with the conductors of the other.
30. 11. In a device of the character described, a channel reflector member, two insulating bases, one adjacent each end of said channel, two lamp receptacles, one supported by each base, each receptacle comprising center 35 and side contacts for the lamp, two conductors extending along said channel member for electrically connecting the contacts of one receptacle with the contacts of the other, and means for mechanically connecting said channel members together end to end to form a unitary structure and for electrically connecting the conductors of one channel with the conductors of the other.
12. In a device of the class described, an elongated channel reflector member, an insulating base secured in fixed position with respect thereto, and a lamp receptacle having a quickly detachable connection with said insulating base, and provided with side and center contacts, and positioned to hold the lamp with its axis substantially parallel to the axis of the elongated channel member, said quickly detachable connection being constructed so that the lamp with its socket may be moved outwardly from the channel member by a swinging movement with respect to said insulating base.

In witness whereof, I have hereunto subscribed my name.

REUBEN B. BENJAMIN.
